UNITED STATES PATENT OFFICE.

WILLIAM H. LONG, OF NEW YORK, N. Y.

PRINTING PRESS.

Application filed February 26, 1919. Serial No. 279,234.

To all whom it may concern:

Be it known that I, WILLIAM H. LONG, a citizen of the United States, and a resident of New York, in the county of New York 5 and State of New York, have invented certain new and useful Improvements in Printing Presses, of which the following is a specification.

The invention relates to printing presses, 10 and more especially to printing presses adapted to either print in a plurality of colors, to perfect the impression receiving material, as may be desired, or to print upon one side of two webs, or other impression 15 receiving material, run through the press together.

The objects and advantages of the invention will be set forth hereinafter in part, and in part will be obvious herefrom, or may be 20 learned by practice with the invention; the same being attained through the instrumentalities and combinations pointed out in the appended claims.

The invention consists in the novel parts, 25 constructions, arrangements, combinations and improvements herein described.

The accompanying drawings, herein referred to and constituting a part hereof, illustrate one embodiment of the invention, 30 and together with the description serve to explain the principles thereof.

Of the drawings:—

Fig. 1 is a side elevation, partially diagrammatic in character, of a press embodying the invention, the cylinders being arranged for multi-color printing, that is for printing two colors on one side of a web;

Fig. 2 is a similar view of Fig. 1, both as to position and character, but showing the 40 cylinders positioned and arranged so as to perfect a web;

Fig. 3 is a view similar in position and character to the preceding views, but showing an arrangement of the cylinders and webs whereby the press prints in one color 45 on one side of each of two webs run together through the press;

Fig. 4 is a fragmentary elevation of a portion of the upper left hand part of Fig. 1, showing particularly the means for moving the form cylinder to and from the large cylinder, dependent upon whether or not the off-set cylinder is interposed therebetween;

Fig. 5 is a fragmentary elevation, on an 50 enlarged scale, of one form of mechanism, shown also in the upper left hand part of

Fig. 3, for moving the off-set cylinder into and out of position between the form cylinder and the large cylinder;

Fig. 6 is an elevation, partly diagrammatic, of the lower part of a press, showing a different form of mechanism for changing the relations of the press cylinders, and showing the off-set cylinder in printing relation with the plate cylinder and impression cylinder;

Fig. 7 is a similar view to Fig. 6, but showing the off-set cylinder out of printing relation, and the plate cylinder cooperating directly with the large cylinder, which may operate as an impression cylinder or as an off-set cylinder; and

Fig. 8 is an enlarged fragmentary detail of the mechanism shown in Figs. 6 and 7 for controlling and adjusting the position of 75 the off-set cylinder.

The press of my invention provides for either multi-color printing, or perfecting a single web, or printing on one side of two webs concurrently by means of changing the positions and relations of the cylinders in accordance with the kind and manner of printing desired; and in accordance with certain features of the invention, it is applied to what is known as "off-set" printing, plate printing, and to a combination of direct plate printing and of off-set printing. Further features and objects of the invention will appear hereinafter in connection with the description of 90 the embodied machine and of the operation thereof.

Referring by way of example to the illustrated embodiment, a form cylinder 1 is provided, having inking mechanism, indicated generally by the reference numeral 2, which mechanism in its details of construction may be of any acceptable or approved form. In accordance with certain features of the invention, the cylinder 1 is constructed and adapted either for printing directly upon a web, or for printing upon an off-set, or rubber-surfaced cylinder, this latter cylinder then printing upon the web.

In carrying out this feature of the invention, there is provided a cooperating off-set cylinder 3, and a cylinder 4. This latter cylinder in the arrangement of the press illustrated in Fig. 1, operates as an impression cylinder, but in the inter-relation of the cylinders shown in Figs. 2 and 3 it is adapted to operate as an off-set cylinder, or as a com-

combined off-set and impression cylinder, receiving the impressions from the cylinder 1 and imparting them to the web as will be later described.

5 Means are provided for changing the positions and inter-relation of the cylinders 1, 3 and 4, for the purposes and objects described, and in the embodied form thereof the cylinder 1 and its inking mechanism 2 10 are mounted upon a frame 5 having base plates 6 and 7 which are slidable on guide-ways 8 and 9 formed on the press frame 10. On the base plates 6 and 7 at either side of the press, are formed gear racks 11 and 12, 15 and meshing with these gear rack bars, respectively, are pinions 13 and 14. Pinions 13 and 14 are fixed upon a shaft 15 which is journalled at 16 and 17 in the press frame. The shaft 15 is provided with a squared head 20 or heads 18 for the application of a crank.

In the embodied form of the invention, the cylinder 1 is adapted to use planographic metal plates stretched upon the surface of the cylinder in a well-known manner. Suitable damping mechanism, which may be of standard or other convenient form, is provided for damping the planographic printing plates preparatory to inking. By reason of the fact that in the present embodiment 25 the direction of rotation of the cylinder 1 is reversed, dependent upon whether it is in direct printing relation with cylinder 3 or cylinder 4, in my preferred embodiment, I provide two damping mechanisms, one such 30 mechanism cooperating with the cylinder 1 while running in one direction, and the other damping mechanism cooperating with the cylinder when it is rotating in the opposite direction, so that the damping operation 35 may in any event precede the inking operation.

In the embodied form thereof, a damping mechanism 23 is provided, mounted upon the frame 10 of the press, and in position to 40 cooperate with the press cylinder 1 when the cylinder 3 is interposed as a printing element or instrumentality between the cylinder 1 and the cylinder 4, as shown in Fig. 1. A second damping mechanism 24 is 45 mounted upon the press frame, and is in position to cooperate with the cylinder 1 when that cylinder is printing directly upon the cylinder 4, and cylinder 4 is operating as an off-set cylinder. The movement of the cylinder 1 from one position to the other brings 50 it into operative relation with either the one damping mechanism or the other.

By rotating shaft 15, cylinder 1 is slid along the press frame 10, to the left-hand 55 position as in Fig. 1 when cylinder 3 is interposed as one of the printing cylinders, and to the right-hand position as in Figs. 2 and 3, when cylinder 3 is out of operative position and cylinders 1 and 4 cooperate directly.

In the first of these two positions, cylinder 1 moves into operative relation with damping mechanism 23 and in the second of these positions cylinder 1 moves into operative relation with damping mechanism 24, as 70 already described.

In the embodied form of means for moving cylinder 3 into and out of operative printing relation with cylinders 1 and 4, and as illustrated in Figs. 2, 4 and 5, cylinder 3 is elevated to what may be termed inoperative or non-printing position and is lowered into what may be termed the operative or printing position. Referring in detail to the embodied means for so raising 80 and lowering cylinder 3, the cylinder is journaled at either end thereof in a journal block 25. Each of the journal blocks is provided at either side with registering recesses 28 and 29 which are in position to co-operate with registering pins 30 and 31. This holds the cylinder firmly to position against the squeeze or pressure of the other cylinders. 85

The illustrated means for raising and lowering the cylinder 3 comprise further lugs 32 fixed to or integral with the journal blocks 25 at either side of the cylinder. These lugs are internally threaded, and vertically disposed screw rods 33 pass therethrough at 90 either side of the press. The screw rods are journalled in top and bottom bearing lugs 34 and 35 on the machine frame at either side. Across the press frame extends a shaft 36, having at either end thereof a pinion 37, which pinions mesh respectively with a diagonal or worm gearing 38 on the bottom end of each of the screw shafts 36. The shaft 36 has a square end 39, whereby it may be rotated, to turn the screw shaft 31 and thereby to raise or lower the cylinder 3 from 95 inoperative or non-printing to operative or printing position and vice versa. 100

Cooperating with the cylinder 4 is a cylinder 45, which is preferably an off-set cylinder and cooperating with cylinder 45 is a plate cylinder 46, which is preferably a planographic cylinder, similar to cylinder 1. Cylinder 46 is provided with an inking mechanism 47 and with a damping mechanism 48 both of which may be of standard or other suitable form. The various cylinders are driven by gearing of suitable design, but which is not shown in the drawing. 110

The manner of operation of the hereinbefore described mechanism, and the arrangements of the web or other impression receiving material for the various ways of printing and interrelation of cylinders, is substantially as follows:

In Fig. 1 a web 50 is shown in a roll at the left hand side, and is threaded through the machine, passing between cylinders 3 and 4, and between cylinders 4 and 45, and 120 125

out of the machine. In the positions and inter-relations of the cylinders shown in Fig. 1, plate cylinder 1 prints upon off-set cylinder 3, which cylinder prints upon the web 50, the cylinder 4 acting merely as an impression cylinder. The plate cylinder 46 prints upon off-set cylinder 45, which in turn prints upon the web 50, as it passes between the cylinder 45 and the cylinder 4, the latter cylinder acting as an impression cylinder. This arrangement of the impression-receiving material and this interrelation on the cylinders provides for printing in two colors upon one side of the web. In Fig. 2 of the drawings, cylinder 3 has been moved to the non-printing or inoperative position, and plate cylinder 1 has been moved into contact with cylinder 4, the impression-receiving material being in the form of a web roll 51 and passing between the cylinder 4 and the cylinder 45. The plate cylinder 1 now prints upon the cylinder 4, which latter cylinder operating as an off-set cylinder prints in turn upon the web 51. Plate cylinder 46 prints upon off-set cylinder 45, in the manner already described, and cylinder 45 in turn prints upon the opposite side of the web 51 from cylinder 4. Cylinders 4 and 45 in this arrangement act as off-set printing cylinders to print upon one side of, and thereby to perfect, the web, each cylinder at the same time acting as the impression cylinder for the other.

In Fig. 3 of the drawings, two webs 52 and 53 of impression receiving material are shown in roll form and as passing between the cylinders 4 and 45, which cylinders operate in the same manner as last described. By reason of the two webs being run together through the press, each web is printed upon one side only, instead of securing a perfected web as is the case when a single web is run through, as shown in Fig. 2. If desired, one of the two simultaneously run webs 51 and 52 may be run from the roll at the top, as shown in Fig. 3, and the other of said webs may be run from the roll 50, as shown in Fig. 1. In this case the web 53 will run through in the manner shown in Fig. 3 and as already described, but the other web will run through in the same manner as the web 50, being printed upon by the plate cylinder 1, the cylinder 4 in this case acting only as an impression cylinder, while the web 53 will be printed by the cylinder 45 in off-set as already described. Driving gears for cylinders 1, 3 and 4 are shown in Figs. 4 and 5, but are omitted from Figs. 1, 2 and 3 for the sake of clearness. It will be understood that the driving connections for the press may be of any usual and suitable character.

In Figs. 6 and 7 are shown a different form of mechanism for changing the relation of the cylinders 1, 3 and 4. In this form or embodiment of the mechanism, the off-set cylinder 3 is moved downwardly, thereby leaving the overhead space free for access to the inking and damping mechanisms, and for other purposes, and the off-set cylinder 3 is also always seated upon and slidable along the press frame.

Referring in detail to the embodied structure, the shaft 55 of off-set cylinder 3 is journaled in bearings on a frame 56 which is slidable on guideways 57 on the press frame. Fixed to the slidable cylinder-carrying frame 56 at either side of the press are geared racks 58. Meshing with the geared racks 58 at either side are corresponding pinions 59, which pinions are fixed on a shaft 60, the shaft being journaled in the press frame. The shaft 60 has squared heads to take a crank, the rotation of the shaft moving the cylinder 3 into and out of printing or operative relation with the plate cylinder 1 and impression cylinder 4.

Means are provided in connection with the last-described mechanism for holding in position and for regulating or adjusting the position of cylinder 3. As embodied, on the bottom end of the slidable frame 56, at either side thereof, are provided a stop and an interponent movable into and out of position, to support the cylinder either in its upper or printing position or in its lower or non-printing position. As shown, the movable stops comprise two arms 61, at either side of the sliding frame 56 and each pivoted thereto at 62.

The cooperating stop, which also provides in this embodiment the regulation or adjustment for the printing pressure or "squeeze", comprises a lug 63 on the press frame, which is internally screw-threaded. Threaded thereinto is a bolt 64, having locking nuts 65 and 66 operating on either side of lug 63. A corresponding device is on each side of the press, and by turning the bolts 64 at either side, the "squeeze" or printing pressure of cylinder 3 is exactly determined or adjusted.

By swinging arms 61 outwardly as shown in Fig. 7, cylinder 3 may be lowered by turning shaft 60 to the position shown in that figure, and plate cylinder 1 moved up to print directly on the web or to print on cylinder 4 as an offset cylinder. The remaining parts of the press may be substantially as already described.

The invention in its broader aspects is not limited to the exact form of mechanism shown and described, but changes may be made therein without departing from the principles of the invention and without sacrificing its chief advantages.

What I claim is:

1. A printing press including in combination an impression cylinder, an offset cyl-

inder, a plate cylinder, and means for moving the offset cylinder into and out of printing relation with the impression cylinder and plate cylinder and for moving the plate cylinder into printing relation either with the impression cylinder or with the offset cylinder to print either directly from the plates or from the offset cylinder.

2. A printing press including in combination an impression cylinder, a plate cylinder movable into and out of direct printing relation with the impression cylinder, and an offset cylinder interposable into and withdrawable from printing relation between the plate cylinder and the impression cylinder.

3. A printing press including in combination an impression cylinder, an offset cylinder, a plate cylinder, and means for moving the offset cylinder into and out of printing relation with the impression cylinder and plate cylinder and for moving the plate cylinder into printing relation either with the impression cylinder or with the offset cylinder to print either directly from the plates or from the offset cylinder, and a plurality of damping mechanisms, one of said damping mechanisms being in operative relation with the plate cylinder when printing on the offset cylinder and another of said damping mechanisms being in operative relation with the plate cylinder when it is printing direct.

4. A printing press including in combination an impression cylinder, a plate cylinder movable into and out of direct printing relation with the impression cylinder, and an offset cylinder interposable into and withdrawable from printing relation between the plate cylinder and the impression cylinder, a damping mechanism in operative relation with the plate cylinder when in direct printing relation with the impression cylinder and another damping mechanism in operative relation with the plate cylinder when it is in printing relation with the offset cylinder.

5. A printing press including in combination an impression cylinder, an offset cylinder, a plate cylinder, and means for moving the offset cylinder into and out of printing relation with the impression cylinder and plate cylinder and for moving the plate cylinder into printing relation either with the impression cylinder or with the offset cylinder to print either directly from the plates or from the offset cylinder, and a printing cylinder also in printing relation to said impression cylinder.

6. A printing press including in combination an impression cylinder, a plate cylinder movable into and out of direct printing relation with the impression cylinder, and an offset cylinder interposable into and withdrawable from printing relation between the plate cylinder and the impression cylinder,

and a printing cylinder also in printing relation to said impression cylinder.

7. A printing press including in combination an impression cylinder, an offset cylinder, a plate cylinder, and means for moving the offset cylinder into and out of printing relation with the impression cylinder and plate cylinder and for moving the plate cylinder into printing relation either with the impression cylinder or with the offset cylinder to print either directly from the plates or from the offset cylinder, and a printing cylinder also in printing relation to said impression cylinder, and means for supplying a web to run between the impression cylinder and both printing cylinders.

8. A printing press including in combination an impression cylinder, a plate cylinder movable into and out of direct printing relation with the impression cylinder, and an offset cylinder interposable into and withdrawable from printing relation between the plate cylinder and the impression cylinder, and a printing cylinder also in printing relation to said impression cylinder, and means for supplying a web to run between the impression cylinder and both printing cylinders.

9. A printing press including in combination an impression cylinder, an offset cylinder, a plate cylinder, and means for moving the offset cylinder into and out of printing relation with the impression cylinder and plate cylinder and for moving the plate cylinder into printing relation either with the impression cylinder or with the offset cylinder to print either directly from the plates or from the offset cylinder, and a printing cylinder also in printing relation to said impression cylinder, and means for directing a web between the impression cylinder and only one of said printing cylinders or between the impression cylinder and both of said printing cylinders.

10. A printing press including in combination an impression cylinder, a plate cylinder movable into and out of direct printing relation with the impression cylinder, and an offset cylinder interposable into and withdrawable from printing relation between the plate cylinder and the impression cylinder, and a printing cylinder also in printing relation to said impression cylinder, and means for directing a web between the impression cylinder and only one of said printing cylinders or between the impression cylinder and both of said printing cylinders.

11. A printing press including in combination an impression cylinder, an offset cylinder, a plate cylinder, and means for moving the offset cylinder into and out of printing relation with the impression cylinder and plate cylinder and for moving the plate cylinder into printing relation either with

- the impression cylinder or with the offset cylinder to print either directly from the plates or from the offset cylinder, and a printing cylinder also in printing relation to said impression cylinder, and means for supplying one web to run between said impression cylinder and only one of said printing cylinders and another web to run between the impression cylinder and the other of said printing cylinders. 10
12. A printing press including in combination an impression cylinder, a plate cylinder and an offset cylinder both movable toward and from the impression cylinder and from each other to bring either two or all three of the cylinders into printing contact together. 15
13. A printing press including in combination an impression cylinder, a plate cylinder, and an offset cylinder both movable toward and from the impression cylinder and from each other to bring either two or all three of the cylinders into printing contact together, and two damping mechanisms in alternative relation with the plate cylinder. 20
14. A printing press including in combination an impression cylinder, a plate cylinder movable into and out of direct printing relation therewith, and an offset cylinder movable from beneath into printing relation between the plate and impression cylinders. 25
15. A printing press including in combination an impression member, an offset member, a plate member, and means for moving the offset member into and out of printing relation with the impression member and plate member and for moving the plate member into printing relation either with the impression member or with the offset member to print either directly from the plates or from the offset member. 30
16. A printing press including in combination an impression member, a plate carrying member movable into and out of direct printing relation with the impression member, and an offset member interposable into and withdrawable from printing relation between the impression member and the plate carrying member. 35
17. A printing press including in combination a member adapted to operate as an impression or offset member and a plurality of printing members movable alternately into and out of direct printing relation with said first member and also with each other. 40
18. A printing press including in combination a cylinder adapted to operate alternatively as an impression cylinder or as an offset cylinder, a plurality of cylinders adapted to cooperate directly with said first-mentioned cylinder and means for running a web between one of said cooperating cylinders and said first-mentioned cylinder or simultaneously between a plurality of said cooperating cylinders and said first-mentioned cylinder, and at least two of said plurality of cooperating cylinders being adapted to cooperate alternatively directly with said first-mentioned cylinder. 45
19. A printing press including in combination a cylinder adapted to operate alternatively as an impression or as an offset cylinder, a plurality of cylinders adapted to cooperate directly with said first-mentioned cylinder and means for running a web between one of said cooperating cylinders and said first-mentioned cylinder or simultaneously between a plurality of said cooperating cylinders and said first-mentioned cylinder, and one of said plurality of cylinders being adapted to cooperate directly with said first-mentioned cylinder or to cooperate therewith indirectly through another of said cylinders acting as an interposed off-set cylinder. 50
20. A printing press including in combination a press frame, a cylinder, a cooperating printing cylinder journaled in a mounting which is slidable on the press frame to bring said cooperating cylinder into and out of printing relation with said first mentioned cylinder, a rack on said slidable mounting, a pinion journaled on the press frame, a stop on the press frame, and an interponent supported on said slid- able mounting and movable into and out of engaging position with said stop, and a screw adjustment for the stop and interponent. 55
21. A printing press including in combination a press frame, a cylinder, a cooperating printing cylinder journaled in a slid- able mounting, guides for the mounting on the press frame inclined from the horizontal, an interponent and a stop therefor, one on said mounting and one on the press frame, a screw adjustment between the interponent and stop, and the interponent being movable into and out of position with respect to the stop. 60

In testimony whereof, I have signed my name to this specification.

WILLIAM H. LONG.
